Husky trash can, announced Oct. 2024 [online], [site visited May 5, 2025]. Avail from int, URL: <https://shorturl.at/dnkSx> (Year: 2024).*

Primary Examiner — Tamara L Hahn

(74) *Attorney, Agent, or Firm* — Thompson Coburn LLP

(57) **CLAIM**

The ornamental design for a heavy duty trash can with lift handle as shown and described.

DESCRIPTION

FIG. 1 is a top perspective view of a heavy duty trash can with lift handle showing our new design;

FIG. 2 is a bottom perspective view thereof;

FIG. 3 is a front elevational view thereof;

FIG. 4 is a top plan view thereof;

FIG. 5 is a bottom plan view thereof; and,

FIG. 6 is a left-side elevational view.

The broken lines in the drawings depict portions of the heavy duty trash can with lift handle that form no part of the claimed design.

1 Claim, 5 Drawing Sheets
